COMBINED GUN EQUILIBRATOR AND ELEVATION CYLINDER

Lawrence Bruehl, Vestal, N.Y., assignor to International Business Machines Corporation, New York, N.Y., a corporation of New York

Filed Sept. 12, 1952, Ser. No. 309,344

13 Claims. (Cl. 89—37)

The present invention relates to improvements in equilibrating systems, elevating systems and shock absorbing systems for guns utilized in tanks. The present invention constitutes an improvement over the equilibrator shown and described in my copending application Serial No. 309,345, filed September 12, 1952.

In the equilibrating system of the aforesaid copending application, there is provided an equilibration cylinder and a separate hydraulic elevating cylinder, which cylinder is also utilized to detect unbalanced forces on the gun.

According to the present invention and in order to provide increased compactness of parts, the elevation cylinder and equilibration cylinder are provided in a single unit. This single unit construction provides increased compactness in parts and provides additional space in the tank turret, and also permits the lowering of the overall height of the tank turret. Combined with the single unit equilibrator and elevator structure, there is provided means for absorbing shocks.

According to the present system, counterbalancing equilibrator pressure is provided, together with means for regulating the equilibration pressure at times when there is an unbalanced force on the gun. Provision is made for detecting the unbalanced force and controlling the regulation of the equilibrating pressure accordingly.

The system of this invention employs a common piston rod which functions in the equilibrator as well as in the elevation system. There is a concentric arrangement of pistons with an inner one for the equilibrator and an outer one for the elevator. Combined with these in the same unit is a pneumatic shock absorber. The shock absorber involves a group of interacting pistons and a gas chamber, the pistons being concentrically disposed with respect to the equilibrator and elevator pistons.

Included in the system is an improved overload bypass for the elevator hydraulic system to prevent building up of excessive stresses when abnormal forces are imposed upon the system.

This invention includes an improved unbalanced force detecting valve which may be located in a separate unit and which acts to control the regulation of the equilibration force being applied to the gun.

By means of this invention, the differential piston unit which was a major element of the older type equilibrator, is entirely dispensed with, which greatly simplifies the system and reduces the amount of material necessary to construct the system. This invention provides a pneumatic system for effecting equilibration in lieu of a fully hydraulic system as formerly employed and provides means for regulating the pneumatic pressure to vary the amount of the equilibration force. Specifically, the improved unbalanced force detecting means, i.e. valves, controls the regulation of the pneumatic force applied by the equilibrator.

Another object of this invention is to provide an elevation cylinder with a shock absorber to elastically cushion the effect of shocks which would otherwise build up excess pressure in the elevating cylinder, with associ-

ated means to allow the escape of liquid from the elevation cylinder and to return the liquid to the cylinder after the effect of the shock has been dissipated.

Other and more detailed objects of the present invention will appear in the following detailed specification and will be pointed out in the appended claims, when considered in conjunction with the accompanying drawings, in which:

Figs. 1a-1d, inclusive, show a schematic layout of the improved equilibrator and elevation cylinder of this invention with the major elements shown in cross-section;

Fig. 2 shows a diagram of the relative positions of the four sheets of drawings which contain Figs. 1a-1d in order to properly join the elements of the system, which

15 are shown on more than one sheet of drawings; and

Fig. 3 shows a fragmentary side view partly in cross-section of an equilibrator-and-elevation cylinder unit mounted on a gun and turret of a tank.

As previously explained in my copending application 20 mentioned above, an equilibrator is a device used in connection with a gun when the gun is mounted with its center of gravity offset from the trunnion axis. These conditions are found almost universally in tanks from force of necessity in the aspects of the design of a tank.

25 The function of the equilibrator then is to apply a counter-balancing force to the gun so that it is in balance about its trunnion axis and may easily be elevated or depressed without undue strain on the elevating mechanism. Because the horizontal distance of the center of gravity of

30 the gun from its trunnion axis varies with the elevational position of the gun, the equilibration force necessary to balance the gun must also be varied. This equilibration force may be made to approach a correspondence with the unbalanced force of the gun by proper geometric arrangement of the points where the equilibrator is attached to the gun and to the turret; however, some discrepancies will be present. In a tank the elevational positions of the gun where discrepancies occur, do not remain constant, e.g. in traveling over rough terrain, the

35 hull and turret will change position relative to the horizon. Therefore, it is on a tank that the system of this invention is particularly beneficial in that this invention permits the continuous regulation of the equilibration force to counter-balance the unbalanced forces of the gun at all times and in all elevational positions.

40 A specific embodiment of this invention is shown in the drawings where Figs. 1a and 1b illustrate a combination equilibration and elevation cylinder and piston device

45 9 which is shown mounted on a gun and turret in Fig. 3.

This unit 9 is operated in conjunction with a hydraulic system illustrated by the Figs. 1a through 1d, which serve to accomplish the purposes set forth above. The combination unit 9 is composed of a piston 10 which has a bracket 12 threaded to the right end of its piston rod

50 11 as viewed in Fig. 1b. The bracket 12 contains a spherical needle bearing 13 (needles not shown) located therein for attaching the unit to either a gun 14 (Fig. 3) or to a turret 15. Piston 10 travels in a cylinder 16 which is located at the right end of the unit as viewed in Figs.

55 1a and 1b. Cylinder 16 is securely attached to the body section 17 of the unit 9. The body section 17 is composed of a number of sections which are all securely fastened together. At the left end of the body section

60 17, there is a bracket member 18 which is fastened to the body section 17 in a similar manner as is the bracket 12 to piston rod 11, and which likewise is for attaching the unit to either the gun or the turret, if the unit is being used in a tank. It will be observed that piston rod 11 is hollow and carries a floating piston 19 inside, which separates the hollow center of piston rod 11 into two sections

65 20 and 21. When the unit is in use, hollow section 20 will be completely filled with hydraulic fluid while hollow

section 21 (to the left of the floating piston 19 as viewed in Figs. 1a and 1b) will be filled with a gas under pressure. Gas under pressure will also fill a hollow chamber 22 of the unit. Chamber 22 is directly connected to section 21 of the hollow piston through a large opening 23.

By a general reference to the unit 9, the operation of the unit to act as an elevation cylinder and also as an equilibration cylinder will now be pointed out. It will be noted that the parts are shown completely telescoped, i.e. elevation cylinder 16 and piston 10 are at one extreme position which produces the shortest distance between the centers of brackets 12 and 18. When used in a tank (as illustrated in Fig. 3 of the drawings), the gun would be at its lowest elevational position (see also the dotted line position 24 of parts in Fig. 3). In order to elevate the gun, hydraulic fluid will be introduced into an annular chamber 28 to the left of piston 10 (see Fig. 1b). This will tend to cause the piston 10 to move to the right, as viewed in the drawings, extending bracket 12 and elevating the gun. Hydraulic fluid which is already in chamber 29 on the other side of piston 10 will be expelled through passage 30 and then on via a hydraulic circuit to be traced later. Equilibration forces are applied to the gun by means of gas under pressure in chamber 22. Such gas will be introduced via passages 31 and 33 (Fig. 1a) in bracket 18. These gas inlet passages 31 and 33 terminate on the outside of bracket 18 by means of an inlet port (not shown) which contains a check valve (not shown) therein to facilitate the charging of chamber 22. Passages 31 and 34 lead to a port 35 to which is attached a gage 32 for determining the pressure existing in chamber 22. As previously mentioned, there is hydraulic fluid in section 20 of piston rod 11, which fluid is, of course, substantially incompressible. Therefore, assuming that there is no change in the quantity of fluid in section 20, the gas under pressure in chamber 22 and section 21 will exert a certain force on piston rod 11. Whenever this force is equal to the unbalanced force of the gun about its trunnion axis (Fig. 3), the equilibrator is working perfectly and needs no regulation. It will be noted, however, that as the gun 14 changes its elevational pistons, the piston rod 11 will be more or less extended, e.g. note dashed line positions 24 and 26 of unit 9 (Fig. 3). Such changes in position of piston rod 11 will correspondingly change the position of floating piston 19 with respect to the body section 17, because the gas pressure in section 21 of the hollow piston rod 11 will hold floating piston 19 in pressure contact with the hydraulic fluid in right-hand section 20 of the piston rod 11. These changes in the position of floating piston 19 with respect to body 17 cause corresponding changes in the volume of the gas chamber made up of hollow chamber 22 and section 21 of the piston rod 11. The change in volume of this gas chamber will change the pressure of the gas within the chamber and consequently will change the equilibration force applied to the gun. Whenever this equilibration force is not equal and opposite to the unbalanced forces of the gun, there will be a tendency for the piston rod 11 to be further extended or for it to be pushed back into the body section 17 depending upon which way the inequality of forces exists. In either case, by sensing means to be described below, such tendency to move piston rod 11 will tend to move piston 10 which is an integral part of piston rod 11 and so will set up unequal pressures on the hydraulic fluid on either side of piston 10. These unequal pressures are used to cause a change in the quantity of hydraulic fluid in section 20 of the piston rod 11 and this, in turn, will move floating piston 19 to the left or right with respect to piston rod 11. This action will compress or expand the gas in chamber 22 and section 21 and correspondingly vary or regulate the pressure of this gas and so correct the equilibration force to make it equal and opposite to the unbalanced force on the gun.

In order to describe the manner in which the regu-

lation of equilibration force as mentioned above is accomplished, the details of the operations of the system will now be described. It will be noted that there is a complete hydraulic system which includes a sump or reservoir 36 (Fig. 1d), a manual pump 37 (Fig. 1c), which has a handle 38, a fragment of which is shown, and a hydro-pneumatic accumulator 39 which provides compressed gas for applying a working pressure to the hydraulic system. Since the system uses very little hydraulic fluid, accumulator 39 could be charged from some other hydraulic system if one is available. Such charging means would be connected to hydraulic pipe 123 (Fig. 1c). Only in very rare cases does it become necessary to operate hand pump 37.

Assuming that system pressure has been obtained by operation of the manual pump 37 to charge accumulator 39, the flow of hydraulic fluid for operating the elevation cylinder and piston will first be traced. Beginning at a hand circulating pump 40 (Fig. 1d), when the handle of 15 circulating pump 40 is rotated in a given direction, hydraulic fluid will be circulated out through pipe 44 to port 45, and thence through a passage 46 to a chamber 47. This chamber and this passage are part of a hydraulic no-back device 48 which operates to allow fluid to be 20 circulated in either direction by the hand circulating pump 40, but which cuts off any return flow of fluid back from the system which might cause the hand pump 40 to motor, i.e. apply rotational force back on the handle of pump 40. Such no-back action is accomplished 25 because of the action both by piston 51, which has two pins 52 and 53 integrally attached thereto, and by means of a pair of spring-loaded check valves 54 and 55. When fluid is circulated from the hand pump 40 into chamber 47, pressure in chamber 47 is increased and piston 51 is 30 moved to the right, as viewed in Fig. 1d. This action causes pin 53 to raise a ball 56 from its seat against the pressure of a spring 57, and so to allow the return fluid to be circulated. At the same time, the pressure increase in the chamber 47 raises ball 59 from its seat 35 against the pressure of a spring 58, which allows circulation of the fluid to continue through a passage 60 and out through hydraulic pipe 61.

The circulation will continue through pipe 62, pipe 45 63 (Figs. 1c, 1b and 1a), pipe 64 to port 65, thence through passage 66, annular chamber 67, upper passage 68, port 69 and hydraulic pipe 70, and from hydraulic pipe 70 to port 71, passage 72 to annular chamber 28. This will then tend to move piston 10 to the right and hydraulic fluid will be returned from chamber 29 via 50 passage 30, a port 76, hydraulic pipe 77, passage 78, annular chamber 79, passage 80, hydraulic pipe 81, passage 82, annular chamber 83, passage 84, hydraulic pipe 85 (Figs. 1a, 1b and 1c), hydraulic pipe 86, hydraulic pipe 87 to port 88 in no-back device 48, and finally 55 through passage 91 past now open valve 55 to chamber 92 and passage 93, hydraulic pipe 94 and back to the hand circulating pump 40 affording a complete circulation of fluid.

Whenever unbalanced forces on the gun exist, which 60 are not counter-balanced by the equilibration section of unit 9, the piston 10 will tend to move in one direction or the other in its cylinder 16. Such a tendency to move by piston 10 will set up a difference of hydraulic pressure on the two sides of this piston. This difference will 65 be detected by a sensing device 98 (Fig. 1c), the action of which will now be described. Assuming the pressure in hydraulic pipe 86 is greater than that in pipe 63, each of which leads back to an opposite side of piston 10 by circuits just traced above, hydraulic pressure in pipe 86 70 will be transmitted via pipe 100 and passage 101 to annular chamber 102 and cause piston 99 to be moved to the left as viewed in Fig. 1c. Movement of piston 99 to the left will cause poppet valve 103 to be opened by means of an integral sleeve 104 of piston 99. Opening 75 of this poppet valve 103 connects an end chamber

109 to a hydraulic circuit that leads to hollow section 20 of piston rod 11 in combination unit 9. This hydraulic circuit is readily traceable and is as follows: from chamber 109, through a passage 105, hydraulic pipe 106 (Figs. 1c and 1b), hydraulic pipe 107, and passage 108 in bracket 12 to hollow section 20. Opening of poppet valve 103 in sensing device 98 therefore connects hollow section 20 of piston rod 11 to system return or the sump 36 (Fig. 1d) by the following hydraulic circuit: beginning at chamber 109, which is directly connected to hollow section 20 as just traced above, the flow of fluid may be past now open poppet valve 103 to annular chamber 110, passage 111, hydraulic pipe 112, hydraulic pipe 113, and hydraulic pipe 114 to the sump 36. This then allows hydraulic fluid to drain out from hollow section 20 of piston rod 11 (Fig. 1b) and therefore allows floating piston 19 to be moved to the right which expands the gas in chamber 22 and hollow section 21 reducing the pressure. The effect of this change is to regulate the equilibration force being applied to the gun. When the unbalance is in the opposite direction and an increase of equilibration force is called for, the hydraulic pressure on the left side of piston 10 will be greater than on the right side and, therefore, this increase of pressure will be transmitted via the hydraulic circuit previously traced to hydraulic pipe 63 and from there to hydraulic pipe 118, passage 119, in the sensing device 98, to annular chamber 120 on the left side of piston 99. This time the action will be the reverse of that just described and piston 99 will be moved to the right whereby its sleeve 121 will cause poppet valve 122 to be opened and this time hydraulic fluid under system pressure will be admitted to hollow section 20 of piston rod 11 by means of the following hydraulic circuit. Beginning at accumulator 39, fluid will flow via hydraulic pipe 123, hydraulic pipe 124, passage 125, annular chamber 126, past the now open poppet valve 122 into end chamber 127. From end chamber 127, fluid may flow through central passages 128, 129 and 130 to end chamber 169 and thence via the hydraulic circuit already traced above to section 20 of hollow piston rod 11. This introduction of hydraulic fluid under pressure from the system will increase the quantity of hydraulic fluid in section 20 of the piston rod and will, therefore, move floating piston 19 to the left which will compress the gas in chamber 22 and in section 21 which in turn will increase the equilibration force being applied by the unit 9.

The poppet valves 122 and 103 of sensing device 98 are held in a seated position as illustrated, by means of springs 135. The amount of spring pressure applied by these springs may be regulated by means of screws 136. There are seals used wherever necessary to isolate hydraulic chambers and the like, throughout the sensing device. The same is true with the other elements of the system, e.g. the equilibration-elevation unit 9 and the no-back device 48. All pistons have rings or some appropriate type of seals to keep any leakage past the pistons to a minimum.

There are three adjustable restrictions in the sensing device 98 which are formed in each case by a needle valve. Each needle valve is composed of a threaded core member 137 which has a slotted top for adjustment by means of a screw-driver and a valve seat 138 which determines the amount of restriction imparted to the flow of hydraulic fluid by the needle valve. The purpose of these needle valves 137 is to restrict the flow of hydraulic fluid in order to throttle the reaction of the sensing means 98 so that it will not be oversensitive. That is, the purpose of the restrictions is to keep the sensing means from reacting to transient shock conditions, such as may be encountered in ordinary travel of a tank over rough terrain. There is only one needle valve 137 for both hydraulic lines leading from each side of elevation piston 10 to the corresponding side of sensing piston 99. This is all that is necessary since any differential

of hydraulic pressure created by forces on the elevation cylinder 16 and piston 10, sets up a tendency for hydraulic fluid to circulate from one side of central piston 99, of the sensing means, to the other. Therefore, whichever direction the fluid is circulating, a restriction in one side is effective to restrict movement of sensing piston 99 and consequently to restrict the sensitivity to transient conditions. On the other hand, restrictive needle valves 137 are necessary in each of the separate hydraulic circuits leading to the system pressure line and to the system return line because these two hydraulic circuits are connected in the alternative to the hydraulic circuit which leads to the equilibration hydraulic system, and when one is connected the other is not, so that a separate restriction is needed for each.

Means to absorb shocks of an appreciable duration as felt by the gun about its trunnion axis, are provided within unit 9. Such means mainly consists of an auxiliary gas chamber 141 (Fig. 1a). This gas chamber is bounded by a pair of annular pistons 142 and 143. Gas chamber 141 will be charged to a predetermined pressure through a vent 144 which is shown closed by a screw 145 having a passage therethrough which contains a check valve (not shown) therein, to hold the gas under pressure as charged into chamber 141. There is a pressure gauge 146 to indicate the gas pressure within chamber 141. The action of gas chamber 141 is to adsorb hydraulic pressure created when some external force is applied to the gun, e.g. when the gun strikes large branches of trees while the tank on which it is mounted is traveling through woods. In addition to such external forces as may be caused by striking external objects, or may be the result of shock loads caused by traveling over rough terrain, the action of chamber 141 and its associated elements is to absorb two types of shocks which occur during firing of the gun. First, there is the shock which occurs as a result of the axis of the gun barrel not intersecting the axis of the trunnion bearings. If the axis of the gun barrel is above or below the axis of the trunnion bearings (above is most common), the gun recoil in firing acts to create a torque about the trunnion axis which tends to whip the gun barrel up or down respectively. This shock load will be absorbed by the shock absorber section presently to be described. Second, there is the shock which occurs when the gun barrel 139 and breach 140 (see Fig. 3) move backwards in their mount 14 (also Fig. 3), which mount has been referred to as the gun 14. Such recoil moves the center of gravity of the whole gun backward rapidly and upsets the state of balance of forces on the gun which was existing due to the equilibrator's action, and this sudden upset creates a shock load on the unit 9 which is absorbed by the same shock absorber section of the equilibrator unit now to be described.

Such deflecting force applied to the gun will tend to move piston 10 within its cylinder 16 and thereby set up hydraulic pressure in the lines leading to either side of piston 10. The pressure thus set up will be absorbed by the gas in chamber 141 which will be compressed by movement of either annular piston 142 or 143. The action of both of these pistons is identical, the only difference being that each one is located in a separate hydraulic circuit, one for each side of piston 10. Therefore, the action of only one of these annular pistons 142 and 143 will be explained in detail.

Assuming a force is applied to the muzzle of the gun tending to elevate the same, piston 10 will tend to move to the right and the pressure of hydraulic fluid in chamber 29 at the right end of piston 10 will be increased. This increase in pressure will be transmitted back through passage 30, hydraulic pipe 77, passage 78, to annular chamber 79. At this point, this increase in pressure will move a sleeve-shaped piston 150 to the left. This piston 150 will in turn move annular piston 142,

against which the left end of piston 150 rests, to the left also. Such movement of piston 142 will compress the gas in chamber 141 which absorbs the shock or overload by allowing fluid to flow into annular chamber 79. Since fluid is allowed to flow into annular chamber 79 from chamber 29, piston 10 will be allowed to move to the right. Therefore, there will be a reduced pressure created on the other side of piston 10 and hydraulic fluid will tend to flow into chamber 28 on the left or low pressure side of piston 10. The source of such fluid will be the annular chamber 67 which is on the opposite side of the fluid-tight piston 150 from the annular chamber 79. In other words, when the shock conditions cause high pressure in the hydraulic fluid lines adjacent to piston 10, sleeve-shaped piston 150, or corresponding sleeve-shaped piston 151, will be moved to the left or to the right respectively, which will absorb these high pressures. Such movement, however, is only possible against the force of gas under compression in chamber 141 and, therefore, when the shock load conditions have ceased, the gas in chamber 141 will move annular piston 142 or 143 back to the position shown which, in turn, will move sleeve piston 150 or 151 back to its extreme position shown, and this movement in its turn will cause a return flow of hydraulic fluid which will reposition piston 10 to the original position within its cylinder 16 where it was before any shock load was felt.

It will be noted that the shock absorbing means just described allows an angular displacement of the gun about its trunnions to take place, but this displacement is absorbed by an elastic medium, namely, gas in chamber 141, so that when the shock load is gone the gun will be returned to its original position by the action of the elastic medium which returns the piston (either 142 or 143) which compressed the gas to its original position, i.e. that shown in the drawings.

To be entirely clear, assume that piston 10 is located in a more or less central position in its cylinder 16 and that a shock load is felt by the system tending to move piston 10 to the left. As soon as the force tending to move piston 10 reaches a predetermined level (which will be determined by the pressure of the gas in chamber 141), the piston will move. This will force hydraulic fluid out of chamber 28, via passage 72, port 71, hydraulic pipe 70, port 69, passage 68, annular chamber 67, passage 66, port 65, pipe 64, pipe 149, passage 148 to annular chamber 147. Here the fluid flowing into chamber 147 will force piston 151 to move to the right, as shown in the drawings, and consequently to push piston 143 to the right, compressing the gas in chamber 141. At the same time, fluid in annular chamber 83 on the other side of piston 151 will be forced out via passage 82, pipe 81, passage 80, annular chamber 79, passage 78, pipe 77, passage 30 to chamber 29, which is on the other side of elevation piston 10. This then supplies the circulation of fluid that is necessary to move piston 10, and the compressed gas in chamber 141 acts as an elastic medium to return the fluid in the reverse circulation to return piston 10 to its original position, after the shock load is gone.

There is a means for taking care of extreme overload conditions of such a magnitude that the various elements of the system might be stressed to the breaking point. This means is composed of a pair of spring-loaded check valves 152 and 153 (Fig. 1c). These check valves are of the ordinary spring-loaded ball type and are constructed with heavy springs 154 and 155 respectively, such that in all normal operating conditions, both valves will remain closed. If extreme loads should be applied to the system, shock absorber chamber 141 would be compressed to its extreme condition first, and then further pressure (which might cause mechanical failure) would be relieved by one of the check valves 152 or 153 depending upon which direction the load is applied to the system. The opening of this valve would allow a by-pass action of hydraulic fluid from one side of elevation piston 10 to the

other as it is moved to relieve the load, and in this case a permanent deflection of the gun will be caused.

The system illustrated is entirely manual in order to simplify the disclosure. However, power elevation or depression of the gun is usually included in an equilibration and elevation system such as that of this invention. This power elevation control may be had when the main hydraulic system of the tank, in which the system is located, is connected into the system. To effect such connection, the pressure side of the main hydraulic system would be connected to the accumulator 39 while the return side would be connected to the sump 36. Therefore, the accumulator 39 would be kept charged up without operating manual pump 37—in the operation of the system as described, it has been assumed that manual pressure pump 37 is being operated whenever necessary to maintain system pressure at a predetermined level—then, in order to control elevation of the gun under power instead of by hand pump 40, there would be a valve, or set of valves (not shown), which would operate to connect the pressure and return sides of the system to the two sides of elevation piston 10 reversibly, depending upon which way the elevation piston was to be moved. Of course, such a valve control would have a neutral position for stopping the elevation piston in any given position. The main hydraulic system would include a power driven circulation pump (not shown) to be connected to the main hydraulic system (which includes accumulator 39 and sump 36) so that the gun might be repositioned in elevation by a power control rather than only by means of a manual pump such as hand pump 40. This system could be made fully automatic by use of gyro responsive valvular means (not shown) which would be connected to hydraulic pipes 61 and 37 over a no-back device (not shown) in a similar manner as the hand elevation pump 40 in Fig. 1a.

There is a drain valve 156 (Fig. 1b) which is connected between hollow section 20 of piston rod 11 and system return or the sump 36. This valve is ordinarily kept shut, its purpose being merely that of draining hydraulic fluid from section 20 of the equilibrator unit 9 when the unit is not in operation.

In the construction of the system, some of the units may be conveniently combined into a single housing, e.g. the sensing device 98, the overload by-pass valves 152 and 153 and the no-back device 48. This is merely a matter of design and does not change the principles of the invention disclosed. A single housing such as just mentioned, might conveniently be mounted in at least three different locations, e.g. by being attached to the cylinder unit 9, to the gun 14, or to the turret 15. The same holds true for hand circulating pump 40. It would be most convenient for the hand pump 40 to be attached to the same thing that the gunner's seat (not shown) is attached to, i.e. the gun 14 or the turret 15, so that there would be no relative motion between the hand pump and the gunner's seat.

There are three chambers 159, 160 and 161 in the unit 9, which are open to the atmosphere and allow free circulation of air by means of vent passages 163, 164 and 165 respectively. The purpose of venting these chambers is to avoid any back pressure from trapped air. These chambers might also be vented to the sump.

The diagram of Fig. 2 is self-explanatory and shows the relative positions of the four sheets of drawings when the connected parts are adjoining one another.

Fig. 3 shows the gun mount 14 mounted on the turret 15 by its trunnions 168, the axis of which is indicated by reference number 25. This figure also shows unit 9 attached to the gun mount 14 and to turret 15 by means of brackets 169 and 170 respectively which are suitably fastened to the gun mount and turret as by bolts shown.

Flexible couplings 171 (Fig. 1b) will be included in the hydraulic pipes at appropriate places in the system, which will be determined by the location of the combined unit 9. For example, with the unit mounted as

shown in Fig. 3, flexible couplings would be necessary at or near the two brackets 12 and 18 of the unit 9, as well as near the gun trunnions 25. Such location of necessary flexible couplings is a matter of designing the system for use in a particular vehicle, e.g. a tank as here illustrated.

A major achievement of this invention is that the gun can be turned smoothly and evenly through its arc with very little unbalance. This is the result of careful mathematical calculations in respect to the linkage mathematics correlated to the gas pressure mathematics (referring to Fig. 3). Both are a function of the three suspension points, viz. the trunnion axis 25, the pivot axis of attachment to the gun by brackets 12 and 169, and the pivot axis of attachment to the ceiling of the turret by brackets 18 and 170. The force exerted by the gun along the line joining the two pivot axes as a function of gun angle represents a certain curve. The counter-balancing gas pressure exerted along the same line as a function of gun angle represents another curve. An outstanding feature of this invention consists in that both curves are calculated so as to have a minimum deviation from each other. In fact in each half of the arc of gun movement there is a point of perfect balance with the plus and minus unbalances cancelling out. In this balance calculation the deviation of the tank off horizontal position was also considered.

Actual tests have shown that shocks of considerable intensity (up to three times gravity) can be absorbed by the equilibrator cylinder unit of this invention and can be damped in 1½ to 2 oscillations with properly calculated dimensions and friction conditions.

Operation

In order to summarize the main features of the invention, the operation of the device will be reviewed. Referring to Figs. 3, and 1a, 1b and 1c, when the gun 14 is static about its trunnion axis 25 relative to the turret 15, the force created by the equilibrator (as determined by the gas pressure in chambers 21 and 22 of the entire unit 9) equals the opposite force created by the torque of the center of mass of the gun which is offset from the trunnion axis 25. The gun may be tilted within a predetermined angular range as limited by the size and location of the parts. Such tilting is accomplished by the elevation cylinder and piston arrangement that includes cylinder 16 (Fig. 1b) and piston 10. Hydraulic fluid is introduced, over the hydraulic pipes illustrated, to one side or the other of the piston 10 within the chamber 29, while the other side of the piston 10 is connected to the return side of the hydraulic system. In this way the piston 10 will be positioned longitudinally within cylinder 16 and so cause a change in the effective length of the entire unit 9, and thereby cause a change in the angular position of the gun 14. If, however, at any time the gun 14 becomes unbalanced about its trunnion axis 25, unequal pressures will be created on the two sides of piston 10. The higher pressure on one side of piston 10 will be transmitted over the hydraulic circuit illustrated to one side or the other of the central piston 99 (Fig. 1c) located in the sensing device 98. At the same time, the other side of this central piston 99 is connected via another hydraulic circuit illustrated to the low pressure side of piston 10. For this reason, the central piston 99 of the sensing device 98 will be displaced either to the left or to the right as viewed in Fig. 1c and will thereby open one or the other of the poppet valves 103 or 122. The opening of one of these poppet valves 103 or 122 will cause hydraulic fluid to be drawn from, or added to, the section 20 (Fig. 1b) of the hollow piston rod 11. In this way the floating piston 19 will be repositioned to the left or to the right within the hollow piston rod 11 and consequently increase or decrease the pressure of the gas contained in chambers 21 and 22 (Fig. 1a) of the

unit 9. Such change of pressure of the gas will change the equilibration force being applied by the equilibrator section of the unit 9, in such a way as to tend to reduce the unbalanced forces on the gun to zero. This action is the same basic situation as that obtained in my co-pending application referred to above, but is here accomplished using a very compact and unitary device.

There is a shock absorber included in the unit 9 which may act throughout the full range of elevation of 10 the gun 14 and which acts in the following manner: The annular chamber 141 has a gas charged therein to a predetermined pressure that may be indicated by the gage 146. This gas under pressure maintains the end walls 142 and 143 of the chamber 141 in their extreme positions as illustrated in Fig. 1a. Whenever a force is applied to the gun that tends to rotate it about its trunnion axis 25, such force will tend to move the piston 10 within its chamber 29 located in the cylinder 16. Such tendency to move the piston 10 will increase 15 the pressure on the hydraulic fluid located on one side of the piston, and when such increase in pressure exceeds a predetermined quantity (as determined by the gas pressure in chamber 141), i.e. assumes shock load magnitudes, either a sleeve shaped piston 150 or a similar 20 sleeve shaped piston 151 will be caused to move from its extreme position as illustrated in Figs. 1a and 1b, to the left or to the right as viewed in the drawings, and will thereby push one of the end walls 142 or 143 a corresponding amount against the pressure of the gas 25 contained in chamber 141. This movement of the piston 150 or 151 will allow hydraulic fluid to flow out of the chamber 29 from the high pressure side of the piston 10 and into the space created by the movement of the piston 150 or 151, and therefore the excessive pressure 30 created by the shock load will be absorbed. At the same time, hydraulic fluid will be introduced into the chamber 29 on the low pressure side of the piston 10 by the same movement of the piston 150 or 151 since such movement will displace hydraulic fluid from the chamber 35 67 or 83 and this fluid will be caused to flow to the opposite side of piston 10. As soon as the excess force of the gun 14 has been dissipated, the gas pressure in chamber 141 will act upon that end wall 142 or 143 which was displaced, and push this end wall back to its 40 extreme position illustrated, while this return action will cause a reverse operation in the flow of hydraulic fluid such that fluid which was removed from one side in piston 10 to chamber 29 will be returned and that fluid which was added to opposite side of piston 10 will be pushed 45 back out of the chamber 29 as the piston 10 is repositioned to its original location. It may be observed that this shock absorbing action will allow the gun to be 50 displaced by an overload or shock while having the gun returned to its original position as soon as the overload or shock condition has been dissipated. Such action may take place anywhere throughout the full range of elevation adjustment of the gun 14.

Though this invention has been described in one embodiment as applied to army tanks, it must be understood that it has many-fold applications such as in derricks, cranes, ships or trains. It can also be applied in many types of stationary tiltable members.

A specific embodiment of the invention has been described in detail but this in no way limits the scope of my invention. Such details are merely illustrative of one specific embodiment. Various changes and modifications will suggest themselves to one skilled in the art. Therefore, I claim as my invention:

1. An improved equilibrator-elevation cylinder unit of 70 the hydropneumatic type for a pivoted member, comprising a compound cylindrical unit having hydraulic cylinder and piston means for elevating and depressing the member, pneumatic chamber means within said unit for applying equilibrating force to the member, sensing means for determining unbalanced forces on the mem-

11

ber, and means associated with said sensing means for regulating the gas pressure of said pneumatic chamber means.

2. An improved equilibrator-elevation cylinder unit of the hydropneumatic type for a pivoted member, comprising a compound cylindrical unit having hydraulic cylinder and piston means for elevating and depressing the member, first pneumatic chamber means within said unit for applying equilibrating forces to the member, second pneumatic chamber means within said unit for absorbing shocks felt by the member, sensing means for determining unbalanced forces on the member, and means controlled by said sensing means for regulating the gas pressure of said first pneumatic chamber means.

3. An improved equilibrator-elevation cylinder unit of the hydropneumatic type for a pivoted member, comprising a compound cylindrical unit having hydraulic cylinder and piston means for elevating and depressing the member, first pneumatic chamber means within said unit for applying equilibrating forces to the member, second pneumatic chamber means with said unit for absorbing shocks felt by the member, sensing means for determining unbalanced forces on the member, and means controlled by said sensing means for regulating the gas pressure of said first pneumatic chamber means, and overload relief means for allowing slippage repositioning of the member before mechanical failure in the equilibrator-elevation unit takes place.

4. An improved equilibrator unit for use with vehicular mounted pivoted members, comprising a unitary cylindrical structure adapted to be pivotally fastened to the vehicle and to the member, said cylindrical structure having a hydraulic member elevating section, a pneumatic equilibration section and a pneumatic shock absorbing section, said hydraulic member elevating section comprising a hollow piston rod having a piston attached thereto, said piston being longitudinally movable in one end of said cylindrical structure for elevating and depressing the member, said pneumatic equilibration section comprising a cylindrical chamber in the other end of said cylindrical structure and extending into said hollow piston rod, a floating piston longitudinally movable within the hollow piston rod and separating gas in said chamber from hydraulic fluid in said hollow piston rod, said shock absorbing section comprising an auxiliary gas chamber having movable walls actuated by hydraulic fluid of said hydraulic member elevating section, hydraulic valve means for sensing unbalanced forces on the pivoted member, and means controlled by said hydraulic valve means for varying the quantity of hydraulic fluid in said hollow piston rod to regulate the equilibration force exerted by the gas in said cylindrical chamber.

5. The combination of claim 4 further including overload relief means for allowing a by-passing of hydraulic fluid from one side of the piston in said member elevating section to the other side thereof whenever a predetermined excessive load is applied to the member in elevation.

6. An improved equilibrator-elevation cylinder unit of the hydropneumatic type for a pivoted member mounted on a vehicle, comprising, a compound cylindrical unit, said unit having means for pivotally attaching its ends to the member and to the vehicle, a hollow piston within said unit, one of said attaching means being integral with said piston, a cylinder having a gas section and a hydraulic fluid section, one end of said cylinder being integral with the other of said attaching means, a floating piston longitudinally movable within said hollow piston to separate said gas section of the cylinder from said hydraulic fluid section, sensing means to determine unbalanced forces on the member, and means controlled by said sensing means for varying the quantity of fluid in said hydraulic fluid section to regulate the pressure in said gas section for regulating the equilibrating force of the equilibrator.

12

7. An apparatus for use with a member which is tiltable about a trunnion axis and which has a center of mass offset from said trunnion axis, said apparatus comprising an equilibrator including piston and cylinder elements to provide varying pneumatic pressure for compensating unbalanced forces attendant upon tilting of the member, hydraulic elevating means for said member including a piston rod which also serves as an element of the foregoing equilibrator.

8. The invention according to claim 7 wherein the hydraulic elevating means includes a piston structure movable with the common piston rod, and a cylinder concentric with said common piston rod.

9. The invention according to claim 7 wherein the common piston rod for the equilibrator and elevating means is hollow and wherein a floating piston is provided in said hollow rod to define a movable boundary between a pneumatic chamber and a hydraulic chamber of said equilibrator, and including means for varying the amount of liquid in the hydraulic chamber to provide varying pneumatic pressures in the pneumatic chamber of the equilibrator.

10. In an apparatus of the class described a hydropneumatic equilibrator for a tilting gun, hydraulic elevating means including an elevating cylinder concentric with a piston rod and also including a piston secured to said piston rod, elements of said elevating means serving also as elements of the equilibrator, said last-named common elements comprising said piston rod which is hollow and including a floating piston in said rod for defining the boundary between the pneumatic and hydraulic sections of the equilibrator, and means for detecting unbalanced hydraulic forces upon opposite sides of said piston with further means controlled by the detecting means for regulating a supply of fluid to the hydraulic hollow section of the equilibrator and for variably displacing the floating piston in the hollow piston rod.

11. A hydropneumatic elevating device for a tiltable gun including an elevating cylinder and piston and double acting means to elastically absorb excess pressures in said elevating cylinder on either side of said piston, said means including means to receive liquid from the excess pressure end of said cylinder, means to introduce a corresponding amount of liquid to the opposite end of said cylinder, and pneumatic pressure means to return the liquid from and to said cylinder when the excess pressure is dissipated.

12. Improved hydropneumatic elevating gear for a gun having trunnions and being mounted on a base for rotation in elevation about the axis of said trunnions, comprising an elevating cylinder and piston connected between said gun and said base for controlling the gun in elevation about said trunnion axis, and shock absorbing means connected to said elevating cylinder including pneumatic cushioning means, means associated with said cushioning means for receiving liquid from the high pressure side of said elevating piston, means for simultaneously supplying a corresponding amount of liquid to the other side of the piston, said cushioning means acting to restore liquid to and from both sides of the piston when the shock has passed.

13. In an apparatus of the class described, a hydropneumatic equilibrator for a tilting gun, hydraulic elevating means for said gun, said last-mentioned hydraulic means having an element which also serves as an element of the foregoing hydropneumatic equilibrator, said element of the hydraulic elevating means which also is the element of the equilibrator comprising a hollow piston rod, and the equilibrator including a floating piston in said hollow rod for defining the boundary between the pneumatic and hydraulic sections of the equilibrator.
